GIDEON SUNDBACK, OF MEADVILLE, PENNSYLVANIA, ASSIGNOR TO HOOKLESS FASTENER COMPANY, OF MEADVILLE, PENNSYLVANIA, A CORPORATION OF PENNSYLVANIA

ARTICLE EMPLOYING FASTENER

Application filed November 9, 1929. Serial No. 406,130.

My invention relates to articles such as wearing apparel and particularly to means for holding portions of such articles in proper position during operation of fastening devices attached to the articles.

In another of its aspects, my invention relates to leggings and particularly to leggings equipped with slide fasteners.

The principal object of my invention is to provide improved means in an article equipped with slide operated fastening means for facilitating the operation of such fastening means.

Another object is to provide an article of wearing apparel embodying a slide fastener with means for anchoring an opening end portion of the fastening device during operation thereof, so that the fastener may be operated by one hand of the wearer.

A further object is to provide an article embodying a slide fastener with detachable strap means adapted to connect the free ends of the edges to be fastened or unfastened and prevent separation of the same during the operation of the fastening device in order to facilitate the operation thereof and to also anchor one opening side portion of the fastener during its operation.

These being among the objects of the present invention the same consists of certain features of construction and combinations of parts to be hereinafter described with reference to the accompanying drawings and then claimed, having the above and other objects in view.

In the drawings which illustrate a suitable embodiment of the present invention;

Fig. 1 is an elevation of an article of wearing apparel embodying my invention.

Fig. 2 is a view similar to Fig. 1 showing the fastener in partly unfastened position and also showing a slightly modified construction.

Fig. 3 is a view similar to Fig. 2 showing the fastener in fully unfastened position.

Considerable difficulty has been experienced in obtaining easy and satisfactory operation of slide operated fastening devices when used in connection with leggings and the like. In the use of leggings and apparel

embodying legging parts, movement of the foot when walking, exerts a tension around the lower edge of the legging which ordinarily tends to move the slider of the fastener and disconnect the interlocked parts of the same. This is a decided disadvantage in an article of this nature.

Another disadvantage in the use of slide operated fasteners in such articles as previously used is the difficulty of opening such fasteners. The edges of the opening end of such fastening devices are not anchored as in the construction of my invention and therefore the interlocking portions of the fastener distort and flex during attempted opening of the fastener whenever the opening ends are not manually held. In the prior construction referred to, the slider sometimes jams so that the wearer is compelled to use both hands to unfasten the garment. One hand would be used to pull on the released end of the garment edge in order to maintain the interlocking portions of the fastener in a straight line while the other hand would operate the slider. The present invention is intended to overcome these disadvantages.

Referring to the accompanying drawings, in which like numerals refer to like parts throughout the several views, the invention is illustrated in connection with a leg covering, such as a knee length legging or one leg portion of a body garment. As shown in Fig. 1, this garment has a leg covering portion 1 and a foot portion 12. The garment is provided with a narrow longitudinal slit 2 at one side extending upwardly from the end of the foot portion 12, the edges 3 and 4 of which are each provided with one stringer 5 of a slide fastener. The fastener stringers 90 are moved into and out of interlocked relation by means of a slider 6 having a pull 7 thereon by means of which the slider is operated.

One end of an instep strap 11 is secured to the side of the foot portion 12 opposite the fastening device. The other end of the strap 11 is preferably bifurcated and one branch is permanently secured to the other side of the leg portion adjacent the edge 3 of the foot 100

portion 12, as shown in Fig. 3. The other branch 9 of the instep strap 11 carries the socket portion 10 of a suitable snap fastener. The foot portion 12 carries the plug portion 8 of the snap fastener at its lower end adjacent the edge 4 of the opening 2, which plug 8 is adapted to be received by the socket portion 10. It is to be understood, however, that a hook and eye, button and buttonhole or any suitable type of separable fastener may be used equally as well as the snap fastener just mentioned. The instep strap 11 may be of elastic webbing, leather, or of the same material as the body of the legging. As illustrated in Fig. 2 this instep strap 11 may be provided with a buckle 13 for adjustment of the length thereof if desired.

In putting on the garment the fastener is open as indicated in Fig. 3 and the wearer 20 adjusts the instep strap to the correct position by slipping it under the heel from the rear. He then moves the slider 6 downwardly by means of the tab 7 to interlock the fastener elements. The socket 10 of the snap fastener is then snapped over its cooperating plug portion 8. The garment then has the appearance illustrated in Fig. 1, with the slider 6 in its lowermost position, which may 30 or may not be covered by the upper end of the instep strap.

To remove the garment the wearer pulls upwardly on the tab 7 of the slider 6 to separate the interlocked sections 5 of the fastener. The strap 11 serves as an anchor 35 for the fastener section 5 adjacent the edge 3 during upward movement of the slider 6. This substantially maintains the section 5 in a straight line so that it will not be distorted 40 and so that it will not be necessary for the wearer to hold the foot portion 12 while the slider is moved. It will be readily seen that if the free end of the edge 3 is not held in anchored position by the instep strap the slider 6 moves hard and tends to jam during its unlocking movement. This generally causes the wearer to use both hands while removing the garment, one hand to support the free end of the edge 3 and the other to 45 move the slider 6. The connection of the free ends of edges 3 and 4 by the end portion 9 of the instep strap 11 serves to prevent unintentional opening of the fastening device. These features of the present invention are 50 particularly advantageous in view of the fact that practically all leg coverings and garments of this type are worn by children.

It is to be understood that the article 60 shown is used for illustration only and that the present invention is equally as adaptable to many other articles, also that various changes may be made in the specific embodiment of the invention described without departing from the spirit and substance of my 65

invention, the scope of which is defined in the appended claims.

What I claim is:

1. An article having a slit therein extending away from an open end thereof, slide 70 fastening means for opening and closing said slit including a slider movable along the same, and a strap portion extending across said open end connecting one side of said article with the other side thereof, one end of said strap being attached to said article on both sides of said slit, said strap providing an anchor for said fastening means during movement of said slider away from the open end of said slit. 75

2. A garment having a slit therein extending away from an open end thereof, interlocking fastener stringers secured to the sides of said slit, a slider cooperating with said fastener stringers for opening and closing 80 the same, and a strap connecting one side of said garment to the other side thereof, one end of said strap being attached to said garment at spaced points on opposite sides of said slit adjacent said fastener stringers to anchor said stringer during the opening movement of said slider. 85

3. A legging having a slit therein, extending upwardly from an edge of the foot portion thereof, interlocking fastener stringers secured to the sides of said slit, a slider operable between said fastener stringers to open and close the same, and an instep strap adapted to extend under the foot of the wearer of said legging, said strap spanning the opening of said foot portion and being secured at one end to said foot portion on both sides of said slit adjacent said fastener stringers to anchor the same during upward movement of said slider. 90

4. In a garment having a slit therein extending from an open end thereof provided with interlocking fastener stringers defining the edges of said slit and a slider for moving said stringers into and out of interlocking engagement, and means for anchoring both of said stringers comprising a strap portion spanning the open end of said garment, one end of said strap portion being bifurcated and secured to said garment on opposite sides of said slit adjacent said fastener. 1

5. A garment having a slit therein extending from an open end thereof, slide fastening means for opening and closing said slit, and a strap having one end bifurcated with one portion permanently secured to said garment at one side of said slit and the other portion detachably connected to the other side of said slit for holding the free ends of the edges of said slit in connected relationship during the opening movement of said fastening means, and the other end of said strap extending around a portion of the body of the wearer and being secured to the other side of said garment, opposite said fastening means. 1

6. A garment having a slit therein extending from an open end thereof, interlocking fastener stringers secured to the edges of the material defining said slit, a slider for moving said fastener stringers into and out of interlocking engagement, and a member spanning opposite sides of said garment adjacent said fastener stringers and secured to said garment at both ends, one of said ends being bifurcated so as to connect to said garment at both sides of said slit, said slider being located between the bifurcated end portions of said strap.

10 7. A garment formed of a continuous piece of material having a slit extending from an open end thereof, slide fastening means for opening and closing said slit, and a strap attached at both ends to said garment at opposite sides of said open end thereof, said strap having a projecting flap spanning said slit and being detachably connected to said garment adjacent an edge of said slit.

15 8. A tubular legging having a foot fitting portion provided with a slit extending from a free edge thereof, interlocking fastener stringers secured to the edges defining said slit, a slider movable along said stringers to move the same into and out of interlocking engagement, an instep strap bridging the 20 sides of said foot portion adjacent to and at one side of said slit, and a flap attached to the last mentioned end of said strap, and detachably connected to said foot portion at the opposite side of said slit, said flap holding 25 said sides of said slit in connected relationship and said instep strap and flap anchoring said sections against distortion during movement of said slider.

9. A legging having a slit therein extending upwardly from its lower end, fastener stringers carried by opposite edges of said slit, a slider movable along said stringers to open and close the same, and an instep strap having a permanent connection at one 40 side of said legging adjacent one of said fastener stringers and rearwardly thereof and an adjustable connection to the opposite side of said legging.

45 In testimony whereof I affix my signature.
50 GIDEON SUNDBACK.
